UNITED STATES PATENT OFFICE.

PATRICK HARVEY, OF CHICAGO, ILLINOIS.

AUXILIARY OVERFLOW FOR LAVATORIES.

SPECIFICATION forming part of Letters Patent No. 299,925, dated June 3, 1884.

Application filed August 20, 1883. (No model.)

To all whom it may concern:

Be it known that I, PATRICK HARVEY, a citizen of the United States, residing at Chicago, in the county of Cook and State of Illinois, have invented certain new and useful Improvements in Auxiliary Overflows for Lavatories, of which the following is a description.

My invention is designed to prevent damage resulting from the overflow of sinks, lavatories, bath-tubs, &c., caused by stoppage of the ordinary waste-drain or overflow-waste passage, while the supply-faucets, through neglect or leakage, continue to run. When such stoppage occurs at the waste-orifice, or in the waste-pipe between the waste-orifice and the junction with the waste-pipe of the overflow-pipe, the latter serves as the relief; but when the stoppage exists in the waste-pipe beyond the junction therewith of the ordinary overflow-pipe, manifestly the latter can give no relief. Such stoppage is most frequent at the traps, which are necessarily beyond the junction of the overflow with the waste-pipe, and at angles or exposed portions of the pipe still further from the bowl. This clogging, when caused by the accumulation of solid matter, particularly greasy matter, is usually gradual, and occurs, therefore, in the ordinary waste-pipe, which is in constant use. A pipe which, on the contrary, should come only occasionally into use as an emergency-pipe, would rarely become clogged during its temporary use in such emergency. This consideration leads to my invention, which consists in providing an overflow-escape independent from and without connection with the ordinary waste-pipe, leading from a point higher than the connections with the waste-pipe, and which may be from the surface of the slab or table in which the basin or tub is set, a channel being provided opening in the edge of the slab at the margin of the bowl, so that the water will escape by it to a safety waste-basin or principal drain or other convenient discharge-point before it rises sufficiently to overflow the entire slab and escape to the floor.

Figure 1 represents a usual form of lavatory with accompanying faucets and waste-escapes, and with my auxiliary overflow attached. Fig. 2 is a vertical sectional view showing my invention as connected with a form of waste-

valve known as "Boyle's waste-overflow." Fig. 3 shows my invention in connection with a bath-tub. Fig. 4 is a detail view of the fitting which I employ in and as part of my invention.

A is the bowl, basin, or tub. B is the supply-faucet. C is the ordinary waste-connection. D is the ordinary overflow. E is the table or slab in which the bowl is set. F is my auxiliary safety overflow-conduit, of which F' is the upper section, having the flanged or flaring end f sunken through the slab E at the lowest point of the cavity G, from which the trough G' leads to the edge of the slab overhanging the bowl. G" is a groove or trough in the slab surrounding the bowl and draining the entire surface into the cavity G. J is a strainer covering the mouth of the conduit F. At the center of it is fixed the ordinary chain stay, K, for the waste-stopper, thereby obviating the necessity for a separate chain stay.

The cavity G and overflow-conduit opening therefrom may be at any convenient part of the slab; but if the slab is at all inclined it should be at the lowest point of the slab, so that the entire surface may be drained into it. When applied to a bowl or sink set in a table or slab, I prefer to make a fitting substantially in the form shown in Fig. 4, wherein the nut K is designed to be clamped below the slab, and thereby to draw the flaring shoulder f down onto suitable packing interposed between it and the upper surface of the slab. When applied to bath-tubs set in wooden slabs, I prefer to connect the auxiliary overflow F with the tub directly, as well as with the surface of the slab, and I have shown such connection in Fig. 3, the duct F" being such direct connection with the tub. When applied in connection with the Boyle overflow-waste, as shown in Fig. 2, my invention takes the form therein shown, the upper end of Boyle's fitting being made so as to be sunken in the slab, and the cover or cap becoming the strainer J. My auxiliary overflow must then be connected into the ordinary overflow, D, at a point higher than that at which the water will lift the float and open the ordinary waste. It is so shown in Fig. 2, opening at d' above the overflow-port d, and leading by an independent course to the sewer or safety-basin.

I do not limit myself to the use of the fitting

described in Fig. 3, which is only a convenient and preferred form.

I claim—

1. In a lavatory, bath-tub, or sink, the combination of a basin, a waste-pipe, and an independent auxiliary overflow escape-conduit connecting with the upper part of the basin, but not with the waste-pipe, so as to relieve the basin when the waste-pipe and ordinary overflow are closed.
2. In a lavatory, bath-tub, or sink, the combination of a basin, a waste-pipe, a containing-slab having the groove in its upper surface, and an independent auxiliary overflow escape-conduit connected with the groove in the surface of the slab, but not with the waste-pipe, substantially as described and shown.

3. In combination with the slab of a wash-basin or sink, having a cavity, G, communicating by a groove or spout, G', with the wash-bowl, a conduit leading from such cavity apart from the ordinary waste-pipe, provided with a strainer, J, over the mouth of such conduit, and a chain stay secured to such strainer, substantially as set forth.

In testimony whereof I have hereunto set my hand, in the presence of two witnesses, at Chicago, county of Cook, and State of Illinois, this 9th day of August, A. D. 1883.

PATRICK HARVEY.
